UNITED STATES PATENT OFFICE.

EMIL H. GRUBBÉ, OF CHICAGO, ILLINOIS.

RAY-TUBE.

1,131,234.

Specification of Letters Patent.

Patented Mar. 9, 1915.

Continuation of application Serial No. 788,597, filed September 8, 1913. This application filed May 27, 1914. Serial No. 841,267.

To all whom it may concern:

Be it known that I, EMIL H. GRUBBÉ, a citizen of the United States of America, and a resident of Chicago, in the county of Cook, 5 State of Illinois, have invented certain new and useful Improvements in Ray-Tubes, of which the following is a specification.

This invention relates to means for cooling the anode member or target of vacuum 10 tubes used in the generation of X and like rays, and has for its object to provide a simple and efficient structural formation and combination of parts whereby a very efficient and positive heat transference is attained 15 during a continued use of the ray-tube, to permit of an extended use of powerful high tension currents which would otherwise damage or destroy the ray-tube after a very short period of actual use, all as will hereinafter more fully appear.

In the accompanying drawings: Figure 1, is a side elevation illustrating the general arrangement of parts of the present invention in an ordinary X-ray tube. Fig. 2, is 25 an enlarged detail longitudinal section illustrating the connection of the adjustable tube or conduit of the present invention and its accessories to the wall of the ray-tube. Fig. 3, is a detail end elevation of the same. Fig. 30 4, is an enlarged detail longitudinal section of the anode or target and its accessories. Figs. 5 and 6, are side elevations illustrating modified arrangements of the parts.

Similar reference numerals indicate like 35 parts in the several views.

The present application is a continuation in part of my prior application for Letters Patent, Serial No. 788,597, filed Sept. 8, 1913.

Referring to the drawings, 1 represents 40 the main bulb of a ray-tube, provided with the usual auxiliary extensions in which are disposed the different members or elements of the ray-tube.

2 is the cathode member, and 3 the anode 45 member or target disposed in any usual opposed relation and having terminal connections extending out through the end walls of individual extensions of the main bulb in any usual and suitable manner.

50 4, is a tubular member of glass or the like, and which may be of an angular form, or a straight form, as shown in the drawings and as found most suitable by the constructor. Said tubular member is disposed in the

interior of the main bulb 1, and in the auxiliary extensions 5 and 6 thereof, with the respective ends of the tubular member fused or similarly secured to the walls of said extensions 5, 6, as shown. The bore of the tubular member 4 contains the heat transference means hereinafter described, and in the present invention its respective ends are open to the atmosphere so that the tubular member will form a ventilating duct or flue for the passage of atmospheric air, to very 65 effectually aid in the removal of excess heat generated during the operation of the ray-tube.

7, is a tube, preferably of metal, disposed longitudinally in one branch of the tubular member 4, aforesaid, with its inner and open end disposed in adjacent relation to the back or rear surface of the anode or target 3, and adapted to discharge a cooling medium against said target as hereinafter more fully 75 set forth. In addition said tube 7 is directly connected to said anode or target 3 by a flexible or elastic conductor 8, so that in the hereinafter described adjustment of the tube 7 to and from the anode or target 3, electrical conductivity will be maintained between 80 the parts, to permit of the use of the tube 7 as a conducting means between the source of electrical supply and the anode or target 3.

9, is a fixed collar secured to the outer end 85 of the auxiliary extension 5, of the main bulb 1, and provided with a central guide hub 10, connected to the collar 9 by radial wings 11, as illustrated in Figs. 2 and 3. The bore of said hub 10, forms a support 90 and guide for the metal tube 7, above described, to maintain the same in proper longitudinal alinement with the other parts of the ray-tube during its various adjustments to and from the anode 3, as above set forth.

12 is a collar or cap secured to the other auxiliary extension 6 of the ray-tube, and constructed in substantially the same manner as the collar 9 above described. Said 100 collar or cap will be provided with an outlet nipple 13, for the attachment of a hose to conduct away the fluid, when a fluid is employed as a cooling medium, as herein-after more fully described.

Air or like gaseous fluid will be employed as the auxiliary cooling medium passing through the tube 7 aforesaid, and supplied

thereto from any suitable source of pressure supply.

14, are a series of heat dissipating fins or projections on the back of the anode or target 3, to aid in the dissipation or transference of the heat generated during continued actual use of the ray-tube.

Having thus fully described my said invention, what I claim as new and desire to 10 secure by Letters Patent, is:—

1. In a ray-tube, the combination of a main body, a tubular member passing through said main body and open at its respective ends to the atmosphere to form a 15 flue, means for effecting a draft through said tubular member, and an anode or target associated with said tubular member within the main body, substantially as set forth.

2. In a ray-tube, the combination of a 20 main body, a tubular member of an angular form passing through said main body and open at its respective ends to the atmosphere to form a flue and an anode or target associated with said tubular member with- 25 in the main body, substantially as set forth.

3. In a ray-tube, the combination of a 30 main body, a tubular member passing through said main body and open at its respective ends to the atmosphere to form a flue, an anode or target associated with said tubular member within the main body, and a tube extending through said tubular member into adjacent relation to the anode aforesaid and adapted to discharge a cool- 35 ing medium against the same, substantially as set forth.

4. In a ray-tube, the combination of a main body, a tubular member passing through said main body and open at its respective ends to the atmosphere to form a flue, an anode or target associated with said tubular member within the main body, and a tube extending through said tubular member into adjacent relation to the anode aforesaid and adapted to discharge a cooling medium against the same, the anode having heat dissipating projections adjacent to the point of discharge from said tube, substantially as set forth.

5. In a ray-tube, the combination of a main body, a tubular member of an angular form passing through said main body and open at its respective ends to the atmosphere to form a flue, an anode or target associated 55 with said tubular member within the main body, and a tube extending through said tubular member into adjacent relation to the anode aforesaid and adapted to dis-

charge a cooling medium against the same, substantially as set forth.

6. In a ray-tube, the combination of a main body, a tubular member of an angular form passing through said main body and open at its respective ends to the atmosphere to form a flue, an anode or target associated 65 with said tubular member within the main body, and a tube extending through said tubular member into adjacent relation to the anode aforesaid and adapted to discharge a cooling medium against the same, the anode 70 having heat dissipating projections adjacent to the point of discharge from said tube, substantially as set forth.

7. In a ray-tube, the combination of a main body, a tubular member passing 75 through said main body and open at its respective ends to the atmosphere to form a flue, an anode or target associated with said tubular member within the main body, and a longitudinally adjustable tube extending 80 through said tubular member into adjacent relation to the anode aforesaid and adapted to discharge a cooling medium against the same, substantially as set forth.

8. In a ray-tube, the combination of a 85 main body, a tubular member passing through said main body and open at its respective ends to the atmosphere to form a flue, an anode or target associated with said tubular member within the main body and 90 a longitudinally adjustable tube extending through said tubular member into adjacent relation to the anode aforesaid and adapted to discharge a cooling medium against the same, the anode having heat dissipating 95 projections adjacent to the point of discharge from said tube, substantially as set forth.

9. In a ray-tube, the combination of a main body, a tubular member of an angular 100 form passing through said main body and open at its respective ends to the atmosphere to form a flue, an anode or target associated with said tubular member within the main body, and a longitudinally adjustable tube 105 extending through said tubular member into adjacent relation to the anode aforesaid and adapted to discharge a cooling medium against the same, substantially as set forth.

Signed at Chicago, Illinois, this 21st day of May, 1914.

EMIL H. GRUBBÉ.
